UNITED STATES PATENT OFFICE.

WILLIAM L. KELLOGG, OF DETROIT, MICHIGAN, AND RICHARD W. BURNETT, OF CHICAGO, ILLINOIS; SAID BURNETT ASSIGNOR TO SAID KELLOGG.

FRICITION DRAFT-GEAR.

1,296,812.

Specification of Letters Patent. Patented Mar. 11, 1919.

Application filed August 13, 1917. Serial No. 185,934.

To all whom it may concern:

Be it known that we, WILLIAM L. KELLOGG and RICHARD W. BURNETT, both citizens of the United States, residing at Detroit, Michigan, and Chicago, Illinois, respectively, have invented certain new and useful Improvements in Friction Draft-Gears, of which the following is a specification.

10 This invention has for its primary object the provision of a compact and efficient friction draft gear of high capacity, in which the resistance to movement of the draw bar increases rapidly from the beginning to the 15 end of its movement under draft or buffing forces, and which provides sufficient reaction only to insure a rapid return of the gear to normal condition when the force is removed.

A further object of our invention is the 20 provision of a friction draft gear which does not require a yoke, and in which the friction elements may be of sufficient size to provide the requisite friction and prevent undue wear, regardless of the distance between the draft lugs on the car to which the draft gear is applied.

Further objects and advantages of our invention will be apparent as it is better understood by reference to the following specification when read in connection with the 30 accompanying drawing, illustrating the preferred embodiments thereof, in which—

Figure 1 is a plan view of the draft gear and coöperating parts of a car;

35 Fig. 2 is a vertical longitudinal section through the draft gear;

Fig. 3 is a rear end elevation of the draft gear the draft sills being in section;

Fig. 4 is a section on the line 4—4 of 40 Fig. 2;

Fig. 5 is a section on the line 5—5 of Fig. 2;

Fig. 6 is a side elevation partially in section illustrating a slightly different form 45 of keeper for the springs;

Fig. 7 is a side elevation illustrating another form of keeper;

Fig. 8 is a detail in elevation of a portion 50 of the structure illustrated in Fig. 7, and

Fig. 9 is a detail in plan illustrating the 55 application of our invention to draft arms intended and adapted for use in tandem spring yokes.

Referring to the drawing, 5 indicates the 55 draft sills of a car to which the draft arms

6 are secured, the latter being provided with forward and rear lugs 7 and 8 respectively. A housing 9 is loosely disposed between the draft arm 6 engaging at either end the lugs 7 and 8. The housing is provided with an 60 integral top plate and flanges 10 at the bottom edges of the side walls to receive a keeper 11 which is secured by a pin 12 extending through openings in lips 13 and fastened by means of a cotter 14. 65

Within the housing 9 and supported by the keeper 11 are two springs 15. Between the springs and the top of the housing, we provide upper and lower friction elements 16 and 17 each having its inwardly directed 70 surface shaped to provide a plurality of intersecting inclined planes. The upper friction elements may be made integral with the housing 9 if desired. A longitudinally movable member 18 having its opposite surfaces 75 similarly formed is disposed between the friction elements 16 and 17 and is provided with forwardly projecting arms 19 between which the butt of the draw bar 21 is disposed and fastened by means of a key 22. 80 The rear end of the member 18 is provided with a tail 23 supported in a yoke 24 which is fastened to the flanges of the draft sills 5 as indicated in Fig. 3. Preferably the member 18 is cored, as indicated in Fig. 2 to 85 reduce the weight thereof.

The upper friction member 16 is provided with lugs 25 which engage the ends of the housing 9 and with lugs 26 disposed in suitable openings in the housing 9 whereby longitudinal movement of the friction member 16 with respect to the housing is effectually prevented. Both the upper and lower friction members 16 and 17 are provided with lugs 27 which engage between corresponding lugs 28 on the inner faces of the walls of the housing 9 to prevent longitudinal movement of either of the members with respect to the housing. It is to be noted that the upper and lower friction members 16 and 17 are interchangeable and that the lugs 26 on the lower friction member 17 prevent lateral movement of the springs 15. 95 100

From the foregoing it will be readily understood that draft or buffing forces are 105 transmitted from the draw bar to the longitudinal friction member 18 and that as the latter moves in either direction under the influence of such forces the friction members 16 and 17 will be separated thus com- 110

pressing the springs 15. The greater portion of the work represented will be absorbed in overcoming the friction between the member 18 and friction members 16 and 17. Additional frictional retardation is provided by the engagement of the edges of the lower frictional member 17 with the walls of the housing and also by engagement of the housing with the lugs 7 and 8. 10 When the force is removed the springs 15 will return the parts to normal condition but in so doing they must overcome the friction between the parts and consequently cannot rebound with sufficient force to damage the car as frequently occurs with draft gears at present in use.

To prevent compression of the springs 15 to a point which will result in breakage thereof, we provide lugs 29 on the member 18. These lugs operate between lugs 28 and 30 on the inner faces of the housing. Thus when the member 18 has reached the desired limit of its travel in either direction, the lugs 29 engage the lugs 28 and 30 and further movement is thereby prevented. 25 Before this can occur, however, substantially all of the work will have been absorbed in overcoming the friction between the surfaces, so that practically no shock will be felt in the car.

In order that the frictional resistance may increase from the beginning to the end of the draw bar movement under draft or buffing forces we preferably cut away the 35 material on the members 16, 17 and 18 at alternate intersections of the planes, forming spaces 31 as clearly shown in Fig. 2. As the member 18 moves in either direction between the friction members 16 and 17 the 40 amount of surface in contact will rapidly increase, thus increasing the frictional resistance to further movement and the wearing surface in contact and prolonging the life of the draft gear.

45 In Fig. 6 of the drawing we have illustrated a slightly different form of our invention in which the keeper 32 is disposed between the side walls of the housing and is provided with an upwardly projecting lug 33. The side walls are provided with openings 34 to receive keys 35 having flanges 36 at their ends. The openings 34 are sufficiently large to receive the flanged ends of the keys 35 which are disposed on either 50 55 side of the lug 33. When the parts are assembled, the springs 37 hold the keys 35 in position to prevent escape of the keeper 33.

In Figs. 7 and 8 we have illustrated another form of our invention in which the 60 keeper 38 is supported on the housing 39 by hook shaped lips 40 engaging stationary pins 41 on the housing and by similar hook shaped lips 42 held in position by a pin 43 passing through the housing 39 and locked by means 65 of a cotter 44. In the last two forms of our

invention the springs are slightly compressed when the parts are assembled.

In Fig. 9 we have illustrated another form of our invention adapted for use with draft arms 45 having a central lug 46 and 70 end lugs 47 intended for use with tandem spring yokes. In this form of our invention the housing 48 is provided with recesses 49 to receive the central lugs 46 on the draft arms. 75

From the foregoing it will be readily understood that we have perfected a very compact and efficient friction draft gear which has numerous advantages over such devices as heretofore known. Our draft gear is relatively inexpensive, may be quickly assembled and is of very high capacity since it will successfully absorb forces which would destroy an ordinary spring draft gear. 80

Various changes may be made in the form 85 construction and arrangement of the parts without departing from the spirit and scope of the invention, or sacrificing any of its material advantages, the forms hereinbefore described being merely preferred embodiments thereof.

We claim:

1. In a friction draft gear the combination of a member adapted to be connected to a draw bar and having its opposite faces formed to provide a plurality of pairs of oppositely directed planes inclined to the longitudinal axis of said member, resiliently biased means capable of movement only in directions transverse to said longitudinal axis 95 and frictionally engaging said planes to retard longitudinal movement of said member a housing embracing said member and resiliently biased means and coöperating lugs on member and housing to positively limit longitudinal movement of said member. 100

2. In a friction draft gear the combination of a member adapted to be connected to a draw bar and having its opposite faces formed to provide a plurality of pairs of oppositely directed planes inclined to the longitudinal axis of said member, a housing embracing said member, friction elements, having coöperating planes, within said housing in both sides of said member and held by said housing against movement in directions parallel to the longitudinal axis of said member and coöperating means on said housing and member to positively limit 110 longitudinal movement of said member. 115

3. In a friction draft gear the combination of a member adapted to be connected to a draw bar and having a face formed to provide a plurality of pairs of oppositely directed planes inclined to the longitudinal axis of said member and resiliently biased means capable of movement only in directions transverse to said longitudinal axis and frictionally engaging said planes to re- 125 130

tard longitudinal movement of said member said planes being cut away at alternate intersections on the member and resiliently biased means respectively to provide increased surface contact as said member moves in either direction.

4. In a friction draft gear for railway cars the combination of a member adapted to be connected to a draw bar and having its opposite faces formed to provide a plurality of pairs of oppositely directed planes inclined to the longitudinal axis of said member, means capable of movement in directions transverse to said longitudinal axis and frictionally engaging said planes to retard longitudinal movement of said member in both directions and a housing enclosing said member and means, said housing being freely movable vertically with relation to the car body.

5. In a friction draft gear for railway cars the combination of a member adapted to be connected to a draw bar and having its opposite faces formed to provide a plurality of pairs of oppositely directed planes inclined to the longitudinal axis of said member, friction elements on both sides of said member having coöperating planes, a housing having means for preventing movement of said elements in directions parallel to said longitudinal axis, means in said housing permitting a limited movement of said elements in directions transverse thereto and a connection between said housing and the car body permitting vertical movement of the former relatively to the latter.

6. In a friction draft gear for railway cars the combination of a longitudinally movable member adapted to be connected to a draw bar and having its opposite faces formed to provide a plurality of pairs of oppositely directed planes inclined to the longitudinal axis of said member, friction elements on both sides of said member having coöperating planes, a housing having means for preventing movement of said elements in directions parallel to said longitudinal axis, resilient means in said housing permitting a limited movement of said elements in directions transverse thereto and a connection between said housing and the car body permitting vertical movement of the former relatively to the latter.

7. In a friction draft gear for railway cars the combination of a longitudinally movable member adapted to be connected to a draw bar and having its opposite faces formed to provide a plurality of pairs of oppositely directed planes inclined to the longitudinal axis of said member, friction elements on both sides of said member having coöperating planes, means for preventing movement of said elements in directions parallel to said longitudinal axis, a housing embracing said member and elements,

springs supported in said housing to resiliently limit movement of said elements in directions transverse to said axis and draft arms on the car body having means to prevent longitudinal movement of said housing while permitting vertical movement thereof.

8. In a friction draft gear for railway cars the combination of a longitudinally movable member adapted to be connected to a draw bar and having its opposite faces formed to provide a plurality of pairs of oppositely directed planes inclined to the longitudinal axis of said member, friction elements having coöperating planes, a housing embracing said member and elements and having means for preventing movement of said elements in directions parallel to said longitudinal axis, said housing being freely movable vertically with relation to the car body, springs supported in said housing to resiliently limit movement of said elements in directions transverse to said axis and a removable keeper to retain said springs in operative position.

9. In a friction draft gear for railway cars the combination of a member adapted to be connected to a draw bar and having its opposite faces formed to provide a plurality of pairs of oppositely directed planes inclined to the longitudinal axis of said member, resiliently biased means capable of movement only in directions transverse to said longitudinal axis and frictionally engaging said planes to retard longitudinal movement of said member in both directions and a housing embracing said member and resiliently biased means, said housing being freely movable vertically with relation to the car body.

10. In a friction draft gear for railway cars the combination of a member adapted to be connected to a draw bar and having its opposite faces formed to provide a plurality of pairs of oppositely directed planes inclined to the longitudinal axis of said member, resiliently biased means capable of movement only in directions transverse to said longitudinal axis and frictionally engaging said plane to retard longitudinal movement of said member in both directions, means to positively limit longitudinal movement of said member, a housing embracing said member and resiliently biased means and connections between said housing and the car body to prevent longitudinal movement of the former while permitting vertical movement thereof relatively to said car body.

11. In a friction draft gear for railway cars the combination of a member adapted to be connected to a draw bar and having its opposite faces formed to provide a plurality of pairs of oppositely directed planes inclined to the longitudinal axis of said member, a housing embracing said member

and connected to the car body, said housing being vertically movable relatively to said car body, friction elements having planes adapted to coöperate with the planes of said member, means on the housing to prevent movement of said friction elements in directions parallel to the longitudinal axis of said member and springs in said housing to

hold said elements in engagement with said member to resiliently retard longitudinal movement thereof.
